CLAIM

U.S. PATENT DOCUMENTS

We claim the ornamental design for a flinger disc, as shown and described.

DESCRIPTION

This application claims the benefit of co-pending U.S. patent application Ser. No. 10/957,876, filed Oct. 4, 2004.

FIG. 1 is a perspective view of the design of the flinger disc of the present invention;

FIG. 2 is a top view of the design of the flinger disc of the present invention;

FIG. 3 is a side view of the design of the flinger disc of the present invention; and,

FIG. 4 is a cross-sectional view, with portions cut away, of the design of the flinger disc of the present invention, taken along reference line 4—4 shown in FIG. 1.
